UNITED STATES PATENT OFFICE.

COLEMAN DORSEY HOBB, OF MIDDLESBORO, KENTUCKY.

LOCK FOR HOPPER-CAR DOORS.

Application filed January 9, 1924. Serial No. 685,234.

To all whom it may concern:

Be it known that I, COLEMAN DORSEY HOBB, a citizen of the United States, and resident of Middlesboro, in the county of 5 Bell and State of Kentucky, have invented certain new and useful Improvements in Locks for Hopper-Car Doors, of which the following is a specification.

My invention relates to improvements in 10 railway car door locks and it consists of the constructions, combinations and arrangements herein described and claimed.

An object of the invention is to provide a simple and efficient lock designed particularly for the doors which close the hopper bottoms of gondola cars.

Another object of the invention is to provide a lock which includes a goose-neck having one position in respect to the gear shaft 20 to lock the hopper door even if unassisted, and another position in respect to said shaft in which the door is permitted to open by the weight of material thereagainst.

Other objects and advantages will appear 25 from the following specification, reference being had to the accompanying drawing, in which,

Figure 1 is a perspective bottom view showing the hopper door locked in the closed 30 position.

Figure 2 is a perspective bottom view showing the first step in unlocking the door,

Figure 3 is a side elevation showing how the weight of material against the door 35 causes the door to open.

Figure 4 is a detail perspective view of the gear shaft as it appears from the side opposite to that in Figure 1.

Figure 5 is a detail section on the line 40 5-5 of Figure 1.

Figure 6 is a detail section on the line 6-6 of Figure 2.

Figure 7 is a detail section on the line 7-7 of Figure 4.

Figures 1, 2 and 3 show enough of a gondola car to illustrate the application of the invention. The invention is a lock for the door lock of the hoppers 2 by which coal or other material is discharged through the 50 bottom of the gondola car 3.

There are two pairs of discharging hoppers. Each pair has doors, but only one pair of the doors and the associated locking mechanism thereof is shown, inasmuch as 55 the construction and operation of both

would be identical. The pair of hoppers 2 to which reference is being made is separated by a space 4 in which the goose-neck 5 of the improved lock operates.

The goose-neck 5 is bifurcated at 6 to receive the solid end of a link 7, the opposite end of which is bifurcated at 8 to receive the arm 9 of the gear shaft 10. The shaft is journaled in suitable bearings 11 crosswise of the car and beneath the hoppers 2.

A bifurcation 12 at the opposite end of the goose-neck 5 receives the head of a bolt 13 which passes through a bar 14 and receives the nut 15 by means of which connection between the goose-neck and the doors 1 70 is made. The nut is kept from turning by a keeper 16 which is suitably fastened on the bar 14. Each door 1 is independently hinged but the bar 14 connects the doors so that they operate as one.

It is to be noted that the goose-neck 5 is of a peculiar curved formation, and it is due to this formation that it has its name. The function of the curved portion 17 is to carry the main center 18 over and below the shaft 80 10 when in the locking position so that the door 1 will be held closed under all circumstances, even in the event of the disconnection of the link 7. The place 19 at which the goose-neck is connected to the bolt 13 85 may be known as the forward center. The place 20 where the link 7 is connected with the arm 9 may be known as the back center. These so-called centers are composed of bolts which provide the necessary pivotal connections between the various parts of the lock. Each bolt 18, for example (Figure 7) has a concealed non-circular head 21 by which the bolt is prevented from turning. The exposed portion 22 of the head may be of circular or other shape. The circular portion occupies a similar opening in the adjacent part 90 of the bifurcation. The bolt passes on through to the other side where it receives a nut 23, this nut being held in place by a suitable cotter 24. This style of fastening is used wherever bolts may be used.

Sleeves 25 on the gear shaft 10 rest against adjacent bearings 11 and hold the shaft in position. A gear 26 on the outer extremity of the shaft 10 meshes with a larger gear 27 on a shaft 28 in a bearing 29 pendant from a plate 30 beneath the outermost hopper 2. The large gear carries an integral handle 31 by which the gear 27 is turned to 110

either lock or unlock the door 1. Lifting up on the handle 31 rotates the shaft 10 so as to close the door. Pressing down on the handle rotates the shaft until the main center 18 is elevated above the shaft whereupon the weight of coal or other material against the door 1 will push on the door and complete the opening.

A throw lever 32 has a passage 33 which 10 frees the handle 31 when the door 1 is in the locked position. This passage is defined by the cam edge 34 of the weight 35 and the lever handle 36 itself. The extremities of both handles 31 and 36 may be 15 so shaped as to receive a short section of pipe to increase the leverage should it become necessary to do so. A bracket 37 (Figure 3) provides the support for the throwing lever 32.

20 Similarly a bracket 38 provides the support for a detent 39 (Figures 5 and 6) which has a recess 40 and heel 41 to receive and support the handle 31 when the lock assumes the operative position in Figure 5. 25 The free end of the detent 39 is weighted at 42 so that gravity holds it in the operative position. It is necessary to raise the detent 39 in order to release the handle 31 from the position in Figure 5. The throwing lever 32 and detent 39 are pivotally mounted at 43 and 44 in the respective brackets. 30 The toe 47 of the detent 39 makes contact with the plate 30 in the holding position (Fig. 5) to prevent the detent from 35 dropping too far and becoming inoperative.

A stud 45 on the weighted end 42 of the detent 39 provides a handle by which the detent may be raised. This stud is designed to receive the end of a pipe, as in an instance 40 already mentioned, by which the leverage may be increased in cases where the pressure of the handle 31 on the heel 41 is too great to be overcome by a pull directly on the stud 45. A keeper 46 provides a place 45 where the lever handle 36 may be locked in order to prevent opening of the door 1.

The operation may be readily understood from the following description. The door 1 remains locked as long as the locking detent 39 remains in the position in Figure 5. In 50 this position the heel 41 supports the handle 31, and a downward pressure on either the handle 31 or the handle 36 of the lever 32 which is intended for this operation will 55 be unavailing in moving the handle 31.

It is through the throwing lever 32 that the gear handle 31 is either moved upward to the locking position or started downward. For these purposes the end of the handle 60 31 is intended to ride in the passage 33. The adjacent longitudinal edges of the passage act as cams in accomplishing the foregoing functions. But before the handle 31 can be moved at all, it is necessary to lift 65 the locking detent 39 so as to move the heel

41 inside of the bracket 38 in order to let the handle pass downward.

A pipe may be fitted over the handle 36 of the throwing lever 32 should difficulty be experienced in starting the handle 31 down. 70 The downward movement of this handle will cause such turning of the gears 26 and 27 that the shaft tends to turn and the main center 18 of the goose-neck 5 will be elevated above the shaft. The pressure of coal or 75 other material inside of the gondola 3 will do the rest. The door 1 will be pushed open and the goose-neck 5 with its associated parts transferred to the position in Figure 3.

80 The link 7 is the actuating member in respect to the positioning of the goose-neck 5. For example, when unlocking the door 1 it is the link 7 that so moves the goose-neck that the main center 18 is elevated above the shaft 10 as already stated. On the other hand, in returning the door 1 to the closed position, it is the link 7 that guides the main center 18 rearward and downward to the locking position below the shaft 10. The curved part 17 of the goose-neck is intended to bear against the collar by which the arm 9 is mounted on the shaft, and this engagement in itself provides a lock for the door 1 which would hold it 90 were all other locking features removed.

95 It is to be observed that most of the parts of the lock are assisted by gravity. Gravity draws the goose-neck 5 downward towards the shaft 10 so that the main center 18 is compelled to seek the lowermost position possible. The door 1 tends to close by gravity and push back on the goose-neck so that this may be accomplished. The locking detent 39 operates by gravity to keep the heel 41 extended beyond the bracket 38, and the action of gravity on the handle 31 while in the locking position assists the function of the locking detent.

100 While the construction and arrangement 110 of the improved gondola car door lock as herein described and claimed is that of a generally preferred form, obvious changes and modifications may be made without departing from the spirit of the invention or 115 the scope of the claims.

115 I claim:—

120 1. In combination with a discharge hopper having a door, a goose-neck pivoted to the door and including a curved portion, a shaft having an arm, a link pivoted respectively to the arm and to the curved end of the goose-neck thereby making a connection, means to turn the shaft in either of two directions so that the arm and link either elevate or lower the curved end pivot behind the shaft and thereby either release 125 or lock the door, a handle included in said turning means, a throw lever by which the handle is actuated, and a locking detent to 130

engage and hold the handle after it has been moved into one position by the throw lever to lock the door in the closed position.

2. In combination with a discharge chute having a door, a goose-neck pivoted at one end to the door, a shaft having an arm, a link pivoted between the curved end of the goose-neck and the arm, a pair of gears for turning the shaft, a handle on one of the 10 gears for operating the shaft to move the curved end pivot of the goose-neck above or below the back of the shaft to either unlock or lock the door, a pivoted throw lever having a passage to receive the handle and 15 move it upward to close the door when the throw lever is moved upward, and a locking detent having a shoulder projectable beneath the handle to hold it in position.

3. In combination with a discharge chute 20 having a door, a goose-neck pivoted at one end to the door, a shaft having an arm, a link pivoted between the curved end of the goose-neck and the arm, a pair of gears for turning the shaft, a handle on one of the 25 gears for operating the shaft to move the curved end pivot of the goose-neck above or below the back of the shaft to either unlock or lock the door, a pivoted throw lever having a passage to receive the handle and 30 move it upward to close the door when the throw lever is moved upward, a locking detent having a shoulder projectable beneath the handle to hold it in position, and a weight so arranged on the locking detent to keep the shoulder projected under the handle by gravity.

4. In combination with a discharge chute having a door, a goose-neck pivoted at one

end to the door, a shaft having an arm and a gear, a link pivoted between the curved 40 end of the shaft, a handle having a gear meshing with the shaft gear for operating the shaft to move the curved end pivot of the goose-neck above or below the back of the shaft to either unlock or lock the door 45 upon moving the handle, a pivoted throw lever having a passage to receive the handle and move it upward to close the door when the throw lever is moved upward, a locking 50 detent having a shoulder projectable beneath the handle to hold it in position, a weight so arranged on the locking detent to keep the shoulder projected under the handle by gravity, and a keeper situated beside the throw lever permitting locking it in that 55 position in which the door is closed.

5. In a device of the character described a plate carrying a bearing bracket, a gear journaled in said bracket and having a 60 handle, a shaft having a gear meshing with the aforesaid gear the shaft being turned when the handle is moved, a goose-neck having means by which it is connected with a door at one end, an arm on the shaft, a link connecting the arm with the curved end 65 of the goose-neck so that the goose-neck is hooked upon or released from the shaft accordingly as the handle is moved, a pair of brackets carried by said plate, a throw lever pivoted in one bracket having a passage to 70 receive the handle and move it to a locking position, and a locking detent in the other bracket having a heel to support the handle when in the locking position.

COLEMAN DORSEY HOBB.
